UNITED STATES PATENT OFFICE.

GEORGE W. MILLER, OF PALISADES PARK, NEW JERSEY, ASSIGNOR TO MILLER AND HEILMAN, OF NEW YORK, N. Y., A FIRM.

TEMPORARY BINDER.

SPECIFICATION forming part of Letters Patent No. 762,182, dated June 7, 1904.

Application filed April 20, 1903. Serial No. 153,484. (No model.)

To all whom it may concern:

Be it known that I, GEORGE W. MILLER, a citizen of the United States, residing at Palisades Park, in the county of Bergen and State of New Jersey, have invented a new and useful Temporary Binder, of which the following is a specification.

This invention is an improved construction of temporary or loose-leaf binder, the object 10 being to provide a cheap and simple device which will open flat when in use, and a still further object is to provide a temporary or loose-leaf binder in which the leaves are secured at a point adjacent their inner edges and 15 which shall be of such construction that when the device is open the leaves will lie perfectly flat and can be conveniently written upon at a point extremely close to their inner edge.

Another object is to provide a temporary or 20 loose-leaf binder from which a leaf can be extracted at any particular point without removing any of the other leaves of the book.

With the objects in view the invention consists, essentially, in providing a two-part back, 25 such parts being hinged together and having the covers flexibly connected to their outer edges, each section of the back being angular in shape and having plates connected to the oblique portions, each plate having a plurality 30 of curved fingers, each plate also having a plurality of apertures adapted to receive the ends of the opposite fingers, the leaves being held upon the fingers, the sections of the back being provided with spring-catches for the 35 purpose of holding the sections locked together.

The invention consists also in certain details of construction and novelties of combination, 40 all of which will be fully described hereinafter and pointed out in the claim.

In the drawings forming a part of this specification, Figure 1 is a perspective view of a temporary binder constructed in accordance with my invention, the same being shown 45 closed. Fig. 2 is a detail perspective view of a temporary binder open. Fig. 3 is a detail perspective view, the leaves being detached; and Fig. 4 is a detail perspective view showing the back open, separating the fingers, showing 50 that the leaves can be removed.

In carrying out my invention I employ a back A and covers B, flexibly connected thereto, said back being made of wood or other suitable material and the covers B of pasteboard or any other suitable material. The back is divided longitudinally into two sections A' and A'', which are hinged together by means of hinges A³. Each section is angular in shape, the inner face of each back-section being of the form of an obtuse angle, the inner portion A' being straight or flat and the outer portion A'' being inclined or oblique, as most clearly shown in the drawings. Each back-section has a metal plate C connected thereto, said plate being arranged adjacent the center of the inclined or oblique portion A'', and each plate has a series of curved fingers D rigidly connected thereto, said fingers being arranged to alternate, as shown in Fig. 4. Each plate also has a series of apertures E, in which the ends of the opposite fingers are adapted to fit when the sections of the back are closed and locked, as shown in Fig. 3, and for the purpose of locking the sections I employ an apertured spring-plate F, 75 which is rigidly attached to one section at the extreme end, the aperture of said plate being adapted to be engaged by a pin G, carried by a spring-plate H, which is secured to the end of the other section, said spring-plate H projecting a sufficient distance beyond the apertured plate F, as shown at H', to permit the end of the finger or thumb to be pressed thereon for the purpose of disengaging the pin from the aperture, and thereby unlock the sections, 80 so that they can be opened or separated, as shown in Fig. 4, and it will be noted that each back-section is cut away adjacent the end, as shown at A'', to provide ample space for the operation of this spring-fastening, it being 85 understood that a fastening is arranged at each end, and in practice I prefer to have them oppositely disposed—that is, at one end the spring-plate F is attached to one section, whereas at the opposite end it is attached to 90 the other section and the spring-plate H correspondingly changed.

It will thus be seen that I provide a cheap and simple construction of temporary binder and one from which the leaves can be quickly 100

and easily extracted or inserted when desired. It will also be noted that by having each back-section constructed with an oblique or inclined portion A⁵ the leaves can be held perfectly flat when the binder is open, and each leaf can therefore be conveniently written upon very close to the inner margin.

Having thus fully described my invention, what I claim as new, and desire to secure by 10 Letters Patent of the United States, is—

A temporary binder comprising a back consisting of two longitudinal sections, angular in cross-section and hinged together, the covers flexibly connected to the outer edges of the 15 oblique portions of the back-section, a metal plate attached to the oblique face of each back-

section, the curved fingers attached to said plates, each plate having openings adapted to receive the ends of the opposing fingers, an apertured plate attached to each of the back-sections adjacent its end and extending across the joint between the back-sections, said plates extending in opposite directions, and the spring-plates carrying the pin adapted to engage the apertured plate, the end portions of 20 the back-sections being cut away or reduced to permit the movement of the spring-fastening device, substantially as set forth.

GEORGE W. MILLER.
